(57) **CLAIM**

The ornamental design for a weightlifting shoe, as shown and described.

DESCRIPTION

FIG. 1 is a rear, top perspective view of a weightlifting shoe, showing my new design;

FIG. 2 is a front, bottom perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof;

FIG. 9 is an enlarged view of detail 9 in FIG. 1; and,

FIG. 10 is an enlarged view of detail 10 in FIG. 5.

The dashed broken lines in the figures are for the purposes of illustrating portions of the weightlifting shoe that form no part of the claimed design.

The dash-dot-dash broken lines are for notating enlarged views and form no part of the claimed design.

1 Claim, 10 Drawing Sheets
